(57) **CLAIM**

The ornamental design for a door hanger, as shown and described.

DESCRIPTION

FIG. 1 is a perspective view showing my new design; FIG. 2 is a front view thereof, the rear view being identical to the front view;

FIG. 3 is a top view thereof;

FIG. 4 is a bottom view thereof;

FIG. 5 is a right side view thereof, the left side view being identical to the right side view; and,

FIG. 6 is a perspective view thereof shown reduced in scale and in an environment of use.

The broken lines represent environment and form no part of the claim.

1 Claim, 5 Drawing Sheets
